(57) **CLAIM**

The ornamental design for a container with pull off cap, as shown and described.

DESCRIPTION

FIG. 1 is a top, front perspective view for a container with pull off cap, showing my new design;

FIG. 2 is a partially exploded, top perspective view thereof, shown with the pull off cap not affixed to the container.

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom view thereof.

The dashed broken lines define the bounds of the claimed design and form no part thereof.
